2 Claims

ABSTRACT OF THE DISCLOSURE

The invention relates to a single waste and vent pipe adapted to be installed in a dwelling wall supported by studding and having side openings for connection to conventional horizontal drain and vent pipes extending from basins, sinks, and other plumbing fixtures. The diameter of the single pipe is less than the larger width of the studding and is substantially constant throughout its length. The waste and vent pipe extends above a ceiling and below a floor of the dwelling.

The present invention relates to waste and vent pipes and more particularly to a vertical waste and vent pipe adapted to be installed within the wall of a house, the wall being constructed of conventional studding. Additionally, the waste and vent pipe is of a length and diameter such that connections to the usual fixtures appurtenant to dwellings can be readily made within the space conforming to conventional stud dimensions. Specifically the waste and vent pipe is one formed from cast iron or other inexpensive materials and has sanitary tapped bosses for suitable connection with basins, sinks, bath tubs, wall hung water closets, and the like.

Most plumbing codes, including that of the Federal Housing Administration and National Plumbing Code require a three-inch main vent. If fittings are required in a space limited by a four-inch wide stud it would be necessary to furr out the wall to accommodate the couplings or fittings since the diameter of the latter would necessitate additional space. Furthermore, walls of extra thickness require the installation of special door jambs. It is, therefore, an object of this invention to provide a waste and vent pipe of sufficient length to extend below the floor of a room as well as above the ceiling to eliminate the use of couplings or fittings in the wall between the ceiling and the floor. At the same time the waste and vent pipe is tapped at such distances from its ends that threaded connections can be made with the fixtures previously mentioned.

Other objects of the invention will be appreciated from the following description taken with the accompanying drawings in which:

FIG. 1 is an elevation of a dwelling, partly in section, illustrating the manner in which a preferred embodiment of the waste and vent pipe is installed; and

FIG. 2 is a front view of a modified form with hub 55 end of the waste and vent pipe shown in FIG. 1.

Referring to the drawings, the dwelling 10 comprises the usual basement 11, floor 12, ceiling 13, and roof 14. The side walls include the conventional 2" x 4" studding 15. The novel waste and vent pipe, shown at 16, is of 60 substantially constant diameter and of such length that it extends below the floor 12 and above the ceiling 13.

2

Disposed between the ends of the waste and vent pipe are sanitary side apertures 17, 18, 19, and 20, each of which is tapped to provide threaded connections with drain pipes leading to wash basins 21, 22, 23, and bath tub 24, respectively. The waste and vent pipe is provided with these apertures during formation thereof since plumbing codes prohibit drilling and/or welding before or after installation of the vent pipe, cast iron having a tendency to crack or split due to uneven heating at localized points or to excessive cutting as by drilling.

In FIG. 1, the upper end of the waste and vent pipe is threaded at 25 to receive fittings or an axially aligned extension 26, the latter having its outlet exterior of the dwelling and being of a greater diameter than that of pipe 16 for the reason that in certain localities the extension must be large enough to prevent frost formation sufficient to choke the vent.

In FIG. 2, the upper end of the waste and vent pipe is provided with a hub bell-shaped enlargement 27 to accommodate the extension. Also the tapped opening 17 for vent connection to fixture 21 is located 42" above the floor.

Since basement walls are usually unfinished and studding is, therefore, not required, the lower end of the vent pipe 16 projects only a short distance below the floor 12. Hence, connection of this end can be made with the hub of an ordinary soil fitting or pipe 28 into which drainage from water closet drain pipe 29 is permitted to flow.

While the waste and vent pipe is illustrated as having four sanitary tapped openings, it is intended that more or fewer openings may be provided if found necessary. The invention is, therefore, subject to such modifications as fall within the scope of the appended claims.

What is claimed is:

1. A vertical waste and vent pipe adapted for installation in a wall supported by studding disposed between spaced flooring and a ceiling, one end of said waste and vent pipe extending below said flooring, the opposite end of said waste and vent pipe extending above said ceiling, the diameter of said waste and vent pipe being substantially constant between its ends, said diameter being less than the larger width of said studding, said waste and vent pipe being provided with a plurality of horizontally directed threaded openings for attachment to and in axial alignment with horizontal drain and vent pipes associated with fixtures, said openings being disposed in the sides of said waste and vent pipe in a common vertical plane, said horizontal pipes being parallel to said wall.

2. A waste and vent pipe as defined in claim 1 in which means are provided at the upper end of the pipe for attachment to a vent extension member.
